US00D469132S

(12) **United States Design Patent**
Song

(10) Patent No.: **US D469,132 S**
(45) Date of Patent: ** Jan. 21, 2003

(54) **MODEL LOCOMOTIVE SMOKE
GENERATOR UNIT**

DESCRIPTION

(75) Inventor: **Byung Moon Song**, Gillette, NJ (US)

FIG. 1 is a top plan view of the model locomotive smoke generator unit, bearing the ornamental design of the invention;

(73) Assignee: **Aristo-Craft/LMP, Inc.**, Irvington, NJ (US)

FIG. 2 is an elevational side view of the model locomotive smoke generator unit, bearing the ornamental design of the invention;

(**) Term: **14 Years**

FIG. 3 is a bottom view of the model locomotive smoke generator unit, bearing the ornamental design of the invention;

(21) Appl. No.: **29/136,911**

FIG. 4 is an elevational end view of the model locomotive smoke generator unit, bearing the ornamental design of the invention;

(22) Filed: **Feb. 9, 2001**

FIG. 5 is an elevational end view of the model locomotive smoke generator unit, opposite to that of FIG. 4, bearing the ornamental design of the invention;

(51) LOC (7) Cl. **21-01**

FIG. 6 is an elevational cross-sectional view of the model locomotive smoke generator unit, bearing the ornamental design of the invention, taken along lines 6—6 of FIG. 3;

(52) U.S. Cl. **D21/561; D21/541**

FIG. 7 is an elevational cross-sectional view of the model locomotive smoke generator unit, bearing the ornamental design of the invention, taken along lines 7—7 of FIG. 3;

(58) Field of Search D21/540, 541,
D21/528; 446/24, 25, 467

FIG. 8 is an elevational cross-sectional view of the model locomotive smoke generator unit, bearing the ornamental design of the invention, taken along lines 8—8 of FIG. 3; and,

(56) **References Cited**

FIG. 9 is an elevational cross-sectional view of the model locomotive smoke generator unit, bearing the ornamental design of the invention, taken along lines 9—9 of FIG. 3.
